United States Patent Office.

JOHN A. MASHMEYER, OF BEARDSTOWN, ILLINOIS.

Letters Patent No. 77,064, dated April 21, 1868.

IMPROVED BUCKLE.

The Schedule referred to in these Letters Patent and making part of the same.

TO ALL WHOM IT MAY CONCERN:

Be it known that I, JOHN A. MASHMEYER, of Beardstown, in the county of Cass, and State of Illinois, have invented a new and improved Buckle; and I do hereby declare that the following is a full, clear, and exact description thereof, which will enable those skilled in the art to make and use the same, reference being had to the accompanying drawings, forming part of this specification.

This invention relates to a new and improved buckle, designed more especially for harnesses, but capable of very general application.

The object of the invention is to obtain a buckle which will admit of the parts it connects being readily attached together and detached, and also readily taken up and let out, and one which will not abrade or injure the parts connected by it in any way whatever.

The accompanying drawings represent—

Figure 1, an outer or face view of my invention applied to a harness-trace and tug.

Figure 2, a longitudinal section of the same, taken in the line x x , fig. 1.

Similar letters of reference indicate corresponding parts.

A represents the body or frame of the buckle, which is slightly curved in a longitudinal direction, and is of skeleton form, or a rectangular frame, with a loop, a , at one end, and a loop, b , at each side, as shown clearly in fig. 1.

B represents the other part of the buckle, which is also a frame, curved longitudinally, and having its sides fitted in notches c c , in the surfaces or edges of the sides d d of the body or frame A.

The outer-end bar e of the part D is provided with a pin or tongue, f , which projects inward at right angles from the outer-end bar e , and the inner-end bar g of B is fitted in a loop in the end of the tug-strap C.

D is the trace, perforated with holes h h , at a suitable distance apart.

The trace passes through the body or frame A of the buckle, inside the end-bars h h , and over intermediate bars i i of the same, whilst the pin or tongue f is passed through one of the holes h h in the trace.

In order to detach the trace, all that is required is simply to shove outward the part B of the buckle, so that the pin or tongue f will pass out of the hole h h in the trace.

This buckle may be plated, japanned, or otherwise ornamented and protected in any proper way. It is strong, neat, and durable, and does not bend or wear either the trace or tug-strap, or other parts to which it may be applied.

I claim as new, and desire to secure by Letters Patent—

A buckle, composed of the two parts, A B, fitted together or arranged substantially as shown and described, and with the pin or tongue f applied to the part B, as set forth.

JOHN A. MASHMEYER.
